STRAIGHT FLOW VOLUME CONTROL
REGISTERWilliam Thomas Truax, Battle Creek, Mich., as-
signor to United States Register Co., Battle
Creek, Mich., a Corporation of Michigan

Application July 30, 1932. Serial No. 626,859

5 Claims. (Cl. 98—101)

This invention relates to straight flow volume control warm air registers or ventilators, and belongs to that type of devices for the passage of air in which the flow is at all times practically directed in a straight course, as it leaves the register. In registers of this type the vanes are arranged to assume when closed positions inclined one to another. When the vanes are fully open they are parallel, and when they are partly open they converge and the air is caused to flow out straight from the opening between the vanes whatever the width of the opening may be. The width of the opening between the vanes obviously controls the volume of the flow.

15 The present invention consists of a special construction and combination of parts for the purpose stated, and the formation preferred and the arrangement thereof are illustrated in the accompanying drawings. Fig. 1 represents a 20 cross section of the frame and vanes fashioned in accordance with this invention and sets forth the parts assembled and in closed position. Fig. 2 is a similar sectional view showing the vanes in open position. Fig. 3 is a section of one corner of the frame. Fig. 4 is a front view of the upper portion of the reticulated face plate of the register with a portion broken away to show the top plate and pivots of the vanes. Fig. 5 is a front view of the lower portion of the register plate with part thereof broken away to disclose the operating members for the vanes. Fig. 6 is a sectional view on broken line 6—6 of Fig. 4. Fig. 7 is a sectional view on broken line 7—7 of Fig. 2.

35 Throughout the description and drawings the same number is used to refer to the same part.

It will be understood that this invention is not limited to any special size or to the precise forms of the parts employed, and it is immaterial 40 whether the vanes are arranged vertically or horizontally, or upon what side of the register the operating members are located.

Considering the drawings, that which is termed the frame in this description is composed of the sheet metal members 1 and 2 connected together in any chosen manner to make a box like rectangular enclosure for the vanes and other elements. At the bottom as best 45 shown in Fig. 7 is the movement plate 3 having a front flange 3' as illustrated, and at the top is a like plate 4. These parts will be again referred to.

The vanes are designated each as a whole by the numbers 5 and 5a. As shown in Figs. 5 and 55 7, the operating member is a threaded key shaft

6, so located as to be reached by a suitable key, not shown, through the register front. Link plates 7 and 7a pivotally engage a threaded block 8 on the key shaft. Those parts rest upon the frame member 1. A sliding plate 9 lies movably upon the movement plate 3 and will be again mentioned.

Reference number 10 designates one of any number of reinforcing bars for the frame connected with the frame member 1 as best shown 65 in Fig. 6.

The part marked 11 is a cylindrical washer as illustrated in Fig. 5 supporting the outer end of the link plate 7 and movable upon the frame member 1.

The reticulated register front 12, which may be of any selected design, is secured by screws 13 and 14 to the flanges 3' and 4' of the movement plate 3 and the top plate 4.

As best delineated in Fig. 1 the vane 5 has a 75 lower flange 15, and an end lip 16. The lip 16, when the vanes are closed engages the side of vane 5a. The vane 5a has a flange 17 and a lower lip 18 which lip when the vanes are closed engages the end of a fellow of vane 5 as 80 illustrated. The vane 5 has a pivot pin 19, and the slide 9 has a lengthwise slot 20 arranged in engagement with the pivot pin 19, so that the slide may move to the left hand as illustrated 85 while engaging the pin. The vane 5a has a pivot pin 21, and the slide has the engaging slot 22. It will be noted in Figs 5 and 7 that the pivot pins are fast to the movement plate 3, and, therefore, the vanes turn slightly on the 90 pivot pins. Vane 5 is turned by means of a pin 23 carried by the slide 9, and as the vane is turned the pin 23 moves with respect to the longitudinal slot 24 in the lower flange 15 of the vane. The vane 5a has towards its lower end in 95 Fig. 1 a vane turning pin 25 carried by the slide 9 and in engagement with the slot 26 in the flange 17 of the vane. It will be further observed in Fig. 1 that the slide 9 has a right angle 100 recess 27 at the left, and when the slide has been moved to open the vanes, the recess 27 engages a stop 28 formed in or upon the movement plate, and the end of the slide 9 marked 29 moves into proximity with the frame member 2. In practice it is customary to stiffen the 105 member 2 by an inwardly pressed bead 30. The portions of vane 5 designated by the reference number 31 in Figs. 1, 2 and 7 are slightly raised ends of the flange 15, so that when the vanes 110 are closed the raised part 31 will pass over the

connecting end of the adjacent and oppositely inclined vane.

As best represented in Fig. 2 the link plate 7 has a pivot pin 32 connecting the link plate 7 with block 8, and a pin 33 pivotally couples the link plate 7 and slide 9. Link plate 7 has its end movably supported upon the frame member 1 as stated and as illustrated in Fig. 5. As the pin 33 must move to the left through the movement plate 3, the slot 34 is formed in that plate. The second link plate 7a is pivoted to the block 8 on its lower side, and has a pivot pin 35 passing upwardly through the movement plate. As slide 9 must move to the left, the upper end of the pin 35 is headed in the movement plate 3 flush with the surface of the plate. The link plate 7 is spaced from frame 1, and carried movably thereon by the cylinder washer 11, and the corresponding end of the link plate 7a is 20 pivotally spaced from the movement plate 3 by a second cylindrical washer 36. The pin 35 is headed in both the frame member 1 and the movement plate 3 as shown in Fig. 4, and holds the washer 36 against displacement at the same time allowing the end of the link plate 7a to turn upon the pin.

In Figs. 4 and 6 is illustrated one of any number and form of springs 37 acting against the frame member 1 and upon the top plate 4, so that the vanes or louvers are held in place pivotally at the top on the top pivot pins 38.

In assembling the parts, take the movement plate 3, the key shaft 6, the link plates 7 and 7a, and the slide 9 and put them in place. The cylinder washers 11 and 36 are also properly placed, and all the vanes or louvers arranged to stand up on the pins. Next take the top plate 4 and enter the pins in the holes of the louvers. Now, the workman can lift the whole assembly and set it in the frame, and the springs will hold it in place. The ends of the re-enforcing bars 10 are next riveted in the frame as shown, and the register is complete. If the key shaft be suitably turned, the threaded block thereon will move into the position of Fig. 2, the link plates will become aligned, the slide will be moved to the left on plate 3, and the louvers opened parallel and at equal distances apart. The air flow is straight. If the vanes or louvers be partly opened, the air flow will converge and pass straight outwardly in a narrower stream. The flow is thus controlled. It is held to be within the purview of this invention to extend the key shaft through the front, and provide a finger piece for turning if desired. As the key shaft is turned to move the block to open the register, its own movement is limited by the stop plate 39 shown in Figs. 1 and 7. The endwise movement of the shaft is thus prevented, and in the closing movement its contrary displacement is prevented by the shoulder 6' against the inside of the flange at the front of the movement plate 3.

Having now described this invention and its mode of operation, I claim:—

1. In a register, the combination with a frame, of vanes operable in the frame, a threaded key shaft, a threaded block actuated by the key shaft, a movement plate, a slide resting and movable on the movement plate, pivot pins projecting from the movement plate, the said slide being provided with longitudinal slots arranged in engagement with the pivot pins, the said slide having projecting vane turning pins, the said vanes having flanges engaging said pivot pins

and provided with lengthwise slots arranged in engagement with said turning pins of the slide, whereby the vanes are turned on the pivot pins when the slide is moved on the movement plate, means for limiting the lengthwise movement of the key shaft, and link plates pivotally connected with the said block and slide and movement plate. 80

2. In a register, the combination with a frame, of vanes operable in the frame, a threaded key shaft, a threaded block operated by the key shaft, a movement plate, said movement plate having a front flange, a reticulated front plate secured to said flange, a slide resting and movable on the movement plate, pivot pins projecting from the movement plate, said slide being provided with longitudinal slots arranged in engagement with said pivot pins, the said slide having projecting vane turning pins, the said vanes having flanges engaging said pivot pins and provided with lengthwise slots arranged in engagement with the turning pins of the slide whereby the vanes are turned on the pivot pins when the slide is moved on the movement plate, means for limiting the lengthwise movement of the key shaft, and link plates pivotally connected with the said block and slide and said movement plate. 90

95

3. In a register, the combination with a frame, of vanes operable in the frame, said vanes having closed positions wherein each vane is in touch with and at an angle with adjoining vanes, a threaded key shaft, a threaded block actuated by the key shaft, a movement plate, a slide resting on and movable on the movement plate, pivot pins projecting from the movement plate, said slide being provided with longitudinal slots arranged in engagement with the pivot pins, the said slide having projecting vane turning pins, the said vanes having flanges engaging said pivot pins and provided with lengthwise slots arranged in engagement with the turning pins of the slide whereby the vanes are turned on the pivot pins when the slide is moved on the movement plate, means for limiting the lengthwise movement of the key shaft, and link plates pivotally connected with the said block and slide and said movement plate. 105

actuated by the key shaft, a movement plate, a slide resting and movable upon the movement plate, pivot pins projecting from the movement plate, said slide being provided with longitudinal slots arranged in engagement with the pivot pins, the said slide having projecting vane turning pins, the said vanes having flanges engaging said pivot pins and provided with lengthwise slots arranged in engagement with the turning

pins of the slide whereby the vanes are turned on the pivot pins when the slide is moved on the movement plate, a top plate in the frame having downwardly projecting pivot pins, said vanes having portions engaging said top pivot pins, means for limiting the lengthwise movement of the key shaft, and link plates connected with the said block and slide and movement plate.
